UNITED STATES PATENT OFFICE.

FREDERICK G. LENTZ, OF LANGHORNE, PENNSYLVANIA, ASSIGNOR TO THE QUAKER MILLS, OF PHILADELPHIA, PENNSYLVANIA, A CORPORATION OF PENNSYLVANIA.

DESIGN FOR A QUILT.

59,018.

Specification for Design. Patented Sept. 13, 1921.

Application filed January 4, 1919. Serial No. 269,702. Term of patent 3½ years.

To all whom it may concern:

Be it known that I, FREDERICK G. LENTZ, a citizen of the United States, residing in Langhorne, Bucks county, Pennsylvania, have invented a new, original, and ornamental Design for a Quilt, of which the following is a specification, reference being had to the accompanying drawings, which form a part thereof.

In the manufacture of quilts, it is customary to associate a body design with a border. A fabric embodying my new design is intended more particularly for use as a body for quilts, although it is adapted

for independent use to form the entire quilt.

The figure is a plan view on a small scale of a portion of the quilt embodying my invention.

I claim—

The ornamental design for a quilt, as shown.

In testimony of which invention, I have hereunto set my hand, at Philadelphia, on this 30th day of December, A. D. 1918.

FREDERICK G. LENTZ.
